PANEL FOR WALLS, CEILINGS, SCREENS
AND THE LIKE

Ruth Asawa Lanier, San Francisco, Calif.

Application May 14, 1956, Serial No. 41,474

Term of patent 14 years

(Cl. D13—1)

Fig. 1 is a front elevational view of a panel for walls, ceilings, screens, and the like, showing my new design.

Fig. 2 is a view in section taken through the line 2—2 in Fig. 1.

Fig. 3 is a view in section taken along the line 3—3 of Fig. 1.

Fig. 4 is a view in section taken along the line 4—4 in Fig. 1.

Fig. 5 is a view taken along the line 5—5 in Fig. 1.

I claim:

The ornamental design for a panel for walls, ceilings, screens and the like, substantially as shown.
